UNITED STATES PATENT OFFICE.

EDWARD V. PRENTICE, OF PORTLAND, OREGON.

COMPENSATING HOLDING DOWN AND SUPPORTING BAR.

Application filed May 16, 1925. Serial No. 30,839.

To all whom it may concern:

Be it known that I, EDWARD V. PRENTICE, a citizen of the United States, residing at Portland, in the county of Multnomah and State of Oregon, and having my post-office address at 1615 Fiske Street, in said city and State, have invented a new and useful Improvement in a Compensating Holding Down and Supporting Bar, of which the following is a specification.

My invention relates to an improvement in a compensating holding down and supporting bar, for use in dry kilns, and is especially useful where dehydrating processes are being carried on and where a compensating support is necessary to compensate for the shrinkage that occurs, as the dehydration process is carried on.

A further object of my invention consists in new, novel and useful means for the compensating for the shrinkage that occurs wherein the supporting bar is made up of a multiplicity of individual unit contacting surfaces, which lie in the same or parallel planes, the same being mounted upon a core bar, adapted to maintain the individual units in slidable relationship with the core bar.

A further object of my invention consists in means for normally maintaining the individual units in spaced relationship with each other and spread apart by compressible spreading means, as coil springs.

A further object of my invention consists in the individual units being mounted upon a core bar, adapted to the prevention of the individual units rotating thereabout and having a suitable seat provided in the ends thereof to properly maintain a coil spring therein.

A further object of my invention consists in a roller support being adapted to the individual units upon the lower layer for contacting with the primary supporting base.

Heretofore in many drying operations, as clay products, where a baking or drying process is carried on, and more especially in the dehydrating of veneers, previously made into panels, wherein the same are piled in considerable heights, a tendency of the lower strata of the panels to pull apart due to the superimposed load, due to the rapid shrinking of the material being dehydrated a device of this character becomes necessary, to compensate for the shrinkage.

My invention is intended as a compensating and spreading means to prevent this

tendency upon the part of material being processed.

With these and incidental objects in view, the invention consists in certain novel features of construction and combination of parts, the essential elements of which are set forth in the appended claims, and to a preferred form of embodiment of which is hereinafter shown with reference to the drawings which accompany and form a part of this specification.

In the drawings:—

Fig. 1 is a side elevation of a supporting track and a supporting carriage placed thereupon, having superimposed a stratified load of material to be placed within the kiln for the kiln drying of the same, and the dehydrating of the product.

Fig. 2 is a fragmentary cross section view, made somewhat in enlarged form to illustrate the application of my device.

Fig. 3 is a fragmentary, side, elevation of a partial unit, made on an enlarged scale to show the relationship of the individual units, mounted upon the core bar, and a means for maintaining the same in spaced relationship upon the core bar.

Fig. 4 is a fragmentary side elevation, partially in section, made to illustrate the adaptation of the coil spring in maintaining the spaced relationship of the individual units upon the core bar.

Fig. 5 is a partial sectional, side elevation of one of the individual units, shown removed from the bar and made to illustrate the seat formed therein for the reception and the retention of the coil spring.

Fig. 6 is a side elevation, partially in section, of one of the individual units, shown removed from the core bar, and illustrating a roller support placed thereunder for contacting with the base support of the carriage upon which the load is placed.

Fig. 7 is a plan, bottom view, of the mechanism shown in Fig. 6 and more particularly made to illustrate the roller support placed thereunder.

Like reference characters refer to like parts throughout the several views.

1 is a supporting track having a carriage 2, disposed thereupon and contacting with the track through wheel supports 3. Of necessity the carriage platform 2, is made of rigid material which may have a metallic metal covering 4, disposed upon the upper surface of the same which I have found will

give satisfactory results if the same is covered with a thin coating of graphite or other lubricating material, but because of the fact that the same is placed in dry kilns where fairly high temperatures are maintained. Because of the further fact that glue material, resinous residues, and other foreign substances are deposited thereupon the platform a satisfactory slippage or compensation, may not always occur between the bar and the base when the bar contacts with a surface of this kind, I have found that more satisfactory results may be obtained where a roller surface is maintained between the compensating bar and the platform structure.

A non-circular core bar 5, is supplied of the approximate width of the platform 2, having disposed thereupon units 6, having disposed therein an opening adapted to the passage of the core bar therethrough that prevents the rotation of the units 6 therearound, held in spaced relationship with each other by compression spring 7, adapted to seat within the individual units by a seating groove 8, disposed within the end of the unit and about the core bar.

Because of the necessity of having different strata of the material being maintained through its transverse length, these bars are cut at a diagonal angle to that of the center line of the core bar, so that the same will contact with the contacting surfaces of the individual units continuously through the transverse length of the material being supported.

A pin stop 9, is disposed in the outer ends of the core bar against which the outer unit composing the compensating bar contacts when in the distended position, and as the material for support shrinks, due to the dehydrating effect, the individual units, composing compensating bar will move inwardly upon the core bar.

To further facilitate the movement of the lower bar upon the platform, I have provided a roller 10, supported upon a suitable journal 11, as shown in Fig. 7, and wherein the roller is almost entirely housed within the base of the individual unit and central of its ends. A metal plate 12, may be disposed upon the platform upon which the lower bar rests and upon which the roller engages.

While the form of mechanism herein shown and described is admirably adapted

to fulfill the objects primarily stated, it is to be understood that it is not intended to confine the invention to the one form of embodiment herein shown and described, as it is susceptible of embodiment in various forms all coming within the scope of the claims which follow:

What I claim is:—

1. A compensating holding down and supporting bar, comprising a core bar, stops disposed at either end of the bar, individual compensating units disposed upon the core bar adapted to having their contacting surfaces lie in the same and parallel planes, a compression spring seated within the adjacent ends of the individual units and adapted to normally maintain the individual compensating units in spaced relationship with each other.

2. A compensating holding down and supporting bar comprising, a core bar, individual compensating units mounted upon the bar, a stop pin located at either end of the supporting bar, and adapted to maintain the individual spaced units therebetween and means for normally maintaining the individual units in spaced relationship.

3. A compensating holding down and supporting bar comprising, a core bar, individual compensating units, mounted upon the bar, normally spaced apart and means disposed in the lower contacting surface of the bar to reduce the friction between the bar and the supporting platform.

4. A compensating holding down and supporting bar, comprising a core bar, individual compensating units, mounted upon the bar, and normally spaced apart by a compressible spring seated in adjacent ends of the individual compensating units and roller supporting means journaled within the base of the individual compensating units composing the bar.

5. A compensating holding down and supporting bar, comprising a core bar, individual compensating units, each forming a parallelogram mounted upon the core bar, compressible spring means adapted to maintain the individual compensating units in spaced relationship upon the bar, locking pins disposed at either end of the core bar, adapted to maintain the individual compensating units upon the bar, and roller supporting means journaled within the base of the individual compensating units.

EDWARD V. PRENTICE.
